UNITED STATES PATENT OFFICE.

OTIS A. HOLLIS, OF KNOXVILLE, PENNSYLVANIA; OLIVE L. HOLLIS AND JOHN F. SANKEY EXECUTORS OF SAID OTIS A. HOLLIS, DECEASED.

CONCRETE CONSTRUCTION.

Application filed September 10, 1924, Serial No. 736,863. Renewed February 9, 1928.

The object which I have in view is an improvement in the methods of concrete construction whereby the building of the same may be greatly facilitated and cheapened.

5 For this purpose I provide a new and improved matrix for concrete construction composed of superimposed courses of matrix boards which form the vertical walls of the matrix and which are held in position by 10 means of transversely disposed horizontal tie bars whose protruding ends are engaged by vertically disposed stay members which support the matrix boards from without.

In matrices of this type, the present practice has been to use for the tie members metal plates whose protruding ends are perforated to receive metal stay rods, and after the concrete is set and the matrix boards and stay rods are removed, these metal plates are 20 knocked lengthwise out of the wall, leaving transverse openings in the latter which must be subsequently plugged with concrete.

In my improved method of concrete construction I use tie members of wire whose 25 protruding ends are looped to receive the stay members, which may be wooden lath, and after the concrete is set and the matrix boards and stay members are removed, I clip off protruding portions of the tie members, leaving the bodies of the same embedded in the concrete wall.

I have invented new and improved tie members for use in this connection.

In the accompanying drawings, Fig. 1 is a 35 view in perspective of a concrete wall which is being erected in accordance with my system; Fig. 2 is an enlarged vertical section of the same; Fig. 3 is a broken side elevation of the finished wall showing some of the tie 40 members clipped off flush with the wall and others unclipped, and Fig. 4 is an enlarged plan view of one of the spreader members.

The following is a detailed description of the drawing.

45 The wall is built up step by step by means of inner end outer matrix boards A which are held in position during pouring, by means of tie members B and vertical stays C. Thus in Fig. 1, I show three superimposed courses of matrix boards, the bottom course indicated at A', the next above at A² and the top course A³. The concrete D is shown poured to the top of the matrix boards A², the matrix boards A³ being set up for further pouring. 50 The tie members B are bent up of wire with the ends of the wire twisted, welded or otherwise secured to hold the shape. These tie members are of sufficient length, so that when laid horizontally, transverse of the wall, their looped ends will protrude sufficiently 60 beyond the matrix boards to receive the vertical stay members C which may be metal rods, but which may be more conveniently and cheaply wooden lath.

In building the wall I first form the footing or foundation E. In the drawings this base is shown cast of sufficient width to support the bottom edges of the lowermost matrix boards A', as shown at 1 in Figs. 1 and 2. The top of the foundation or footing 70 course is levelled off horizontally. The bottom row of tie members B are then laid on the top of the base course, the matrix boards A' are placed in position and the stay members C are slipped through the protruding 75 loop ends of the members B. Additional tie members B are then slipped down over the stay rods and rest on the top of the matrix boards A'. Wooden struts such as F in Fig. 1 are then inserted between the matrix boards to hold them vertically against the stay rods. The concrete D is then poured between the matrix boards A' and smoothed off level to the top of the matrix boards. Before the cavity 80 between the matrix boards A' is completely 85 filled, the wooden struts F are knocked out and their place filled with the concrete.

The next course of matrix boards A² is now placed in position, and additional tie members B are placed on top thereof with 90 their ends engaging the stay members C, and the struts F are interposed between the matrix boards A². The operation of pouring and filling the cavity between the matrix boards is then repeated and the next course 95 of matrix boards A³ is placed in position in the same way, the operation being continued until the desired height of the wall is obtained.

The tie members B are so arranged that 100 they may each accommodate more than one stay member C at each end so that the stay members may be overlapped, as shown in Fig. 1 to avoid interruption in the support of the adjacent courses of matrix boards.

105 As the concrete sets and hardens the matrix boards may be removed in turn from below, by slipping out or breaking away the stay rods and lifting off the matrix boards, leaving the ends of the tie members protruding, as 110

shown at the right in Fig. 3. The protruding ends of the tie members are then snipped off flush with the concrete of the wall as shown at the left in Fig. 3, leaving the body of the tie members permanently embedded in the concrete.

In Fig. 4 I show a convenient form of tie member formed of wire and consisting of the longitudinal side portions 2, the transverse end portions 3 and the intermediate longitudinal leg 4. This form of tie member provides means for securing thereto two stay rods at each end. The tie members may be conveniently made by bending up the wire to the proper form and then welding or otherwise securing the ends together. Thus the wire is shown welded together at 5. It is of course apparent that the tie members may be provided with any form of looped end into which stay members may be inserted or by which they may be secured, but I prefer the particular embodiment of the tie member which I show in the drawings.

It is evident from the foregoing that my invention greatly facilitates the building of a concrete wall, as the wire tie members can be quickly laid in position and after the matrix boards are removed their protruding ends may be easily snipped off. No extra labor is thus required to plug the holes in the wall of the concrete, thus effecting a material saving in time and labor, and insuring a solid wall. My improved form of spreader member is much less expensive than the metal plate, and the assemblage and disassemblage of the matrix is a much quicker operation than where metal tie plates and metal stay rods are used. Again, the permanent embedding of the bodies of the tie members in the concrete wall acts to reinforce the wall instead of weakening it, as where transverse apertures

are left by the knocking out of the tie members, even when the latter are plugged as well as possible with concrete. The use of my improved tie members also enables me to use ordinary wooden lath for the ordinary stay members, thereby working an additional economy.

These laths, or other equivalent members of relatively yielding material, have a further advantage over metal rods which is of very substantial practical importance. When the form of matrix is assembled as shown in Fig. 1, and the struts F are positioned to space the boards, a certain degree of tension is imposed on the wire tie member B, causing them to bite into the lath slightly and giving a very firm grip on such members, which in turn press tightly upon the sides of the matrix boards. The frictional contact between each lath and the plurality of boards which it overlaps, ties the superimposed courses of boards together and stiffens the structure against an end-wise or racking movement, so that the form or matrix, as a whole, is much firmer and stiffer than a structural material employing metal rods instead of lath or other equivalent yielding material into which the tie members can bite. The laths are also very positively held by the bite of the wire against accidental displacement.

What I desire to claim is:

For use for the purposes described in connection with concrete construction, tie members formed of bent wire and comprised of three parallel spaced apart legs, and end members connecting the ends of said legs, substantially as described.

Signed at Pittsburgh, Pa., this 8th day of Sept., 1924.

OTIS A. HOLLIS.
